PRESSER FOOT LIFTING ATTACHMENT
FOR SEWING MACHINES

Lee C. Preston, Oakdale, Calif.

Application March 3, 1950, Serial No. 147,420

6 Claims. (Cl. 112—239)

I This invention relates to a novel sewing machine attachment primarily adapted for use on sewing machines used in shoe repair work or for sewing leather and which may also be applied to other types of sewing machines used for sewing cloth and other material.

More particularly, it is a primary object of the present invention to provide a sewing machine attachment of extremely simple construction which may be quickly and easily applied to or removed from a sewing machine and which is so constructed that it will fit sewing machines of different models and makes to thereby afford substantially a universal attachment.

It is a primary object of the present invention to provide an attachment which is detachably connected to the presser foot bar of a sewing machine and includes a portion which is disposed above and in the path of movement of the end of the sewing machine lever which connects with the needle bar whereby when the needle bar and needle carried thereby are raised by upward swinging movement of said lever end, the attachment will be carried upwardly with the lever end for raising the presser foot bar and presser foot so that the material being sewed may be turned as desired, thus enabling two pieces of material to be sewed together in edge abutting engagement without overlapping of the pieces and by making a smooth cross stitch through the ability of the operator to turn the two pieces of material each time that the presser foot is thus raised.

Still another object of the invention is to provide a sewing machine attachment which may be readily rendered inoperative without being dismounted from the machine enabling the attachment to remain in an applied position yet to be used only when desired.

Numerous other objects and advantages of the invention will hereinafter become more fully apparent from the following description of the drawings, illustrating a presently preferred embodiment of the invention shown applied to different types of sewing machines, and wherein:

Figure 1 is a fragmentary perspective view of one form of sewing machine showing the attachment applied thereto and in an operative position;

Figure 2 is an exploded perspective view of the attachment dismounted;

Figure 3 is an exploded longitudinal sectional view partly in side elevation illustrating all of the parts of the attachment;

Figure 4 is a perspective view of one part of the attachment;

2 Figure 5 is an end elevational view partly in vertical section of the parts as illustrated in Figure 1;

Figure 6 is a view similar to Figure 5 but showing the attachment applied to another type of sewing machine;

Figure 7 is an end elevational view, partly in vertical section of a third type of sewing machine showing the attachment applied thereto, and

Figure 8 is a fragmentary plan view showing portions of two pieces of material stitched together in edge abutting relationship and by a cross stitch formed by any one of the sewing machines utilizing the attachment.

Referring more specifically to the drawings, the attachment for sewing machines comprising the invention and illustrated in detail in Figures 2, 3 and 4 includes a barrel member 10 having a bore 11 of circular cross section which is provided with a threaded end 12 which opens outwardly of the lower end of the barrel member 10. The bore 11 is provided with a restricted, non-circular upper end 13 which opens outwardly of the upper end 12 of said barrel member 10. The barrel member, adjacent its upper end, is externally restricted to provide a non-circular portion forming wrench lands 14.

A head 15 is slidably disposed in the bore 11 and is sufficiently large to prevent it from passing through the restricted bore portion 13. The head 15 is provided with a restricted extension 16 of non-circular cross section which is sized and shaped to fit non-rotatably in the restricted bore portion 13. A rod 17 is fixed to and projects from the restricted shank 16 in a direction longitudinally of the barrel portion 10. The rod 17 is bent intermediate of its ends to provide a free end portion forming an arm 18 which is disposed substantially at a right angle to the remainder of said rod 17. The rod 17 is bent to provide the arm 18 after it has been passed upwardly through the bore 11 and the restricted bore portion 13. An expansion coiled spring 19 is disposed within the bore 11 beneath the head 15.

The attachment also includes a threaded connecting member, designated generally 20 comprising a body of circular cross section as seen at 21 and which is threaded throughout its length 50 and which is provided with a kerf 22 at one end thereof and a restricted threaded shank 23, which projects from its opposite end.

The attachment also includes a tension plate engaging block 24 having a recess 25 which opens 55 outwardly of three sides thereof and which divides the block into a top wall 26 and a bottom portion

which is likewise recessed to provide spaced furcations 27, defining a slot 28 therebetween. The furcations 27 are preferably beveled on their undersides and toward their free ends, as seen at 29. The top wall 26 is provided with a threaded opening 30 which opens into the recess 25 and aligns with the slot 28.

Figures 1 and 5 show the sewing machine attachment applied to one type of sewing machine known as the "Singer sewing machine model 29-4." Only such of the parts of the sewing machine, designated generally 31, which function with the attachment have been illustrated and which include the end of the actuating lever 32 which is connected to the needle bar 33 and the presser foot bar 34, the upper end of which extends into an opening 35 formed in the tension plate 36, adjacent the free end of said plate. The upper end of the presser foot bar 34 is provided with a tapped recess 37 which is normally engaged by a fastening, now shown, for connecting the presser foot bar 34 to the tension plate 36 but which is removed when the attachment is employed. To apply the attachment, the block 24 is applied to the free end of the tension plate 36 so that said end will engage the recess 25 and with the furcations 29 straddling a portion of the presser foot bar 34 and the threaded opening 30 aligning with the tapped recess 37. The stem 24 of the connecting member 29 is then threaded through the opening 30 and into the threaded recess 31 for connecting the block 24 to the presser foot bar 34 and tension plate 36 so that said parts may not move relatively to one another and to prevent the presser foot bar 34 from sliding upwardly through the opening 35 of the tension plate 36, above its position of Figure 5. The internally threaded end 12 of the barrel 10 is then threaded to the upstanding threaded portion 21 of the connector 20 which rises from the block 24 for mounting the barrel 10 thereon, including the parts carried thereby. The spring 19 is compressed between the head 15 and the upper end of the connector 20 to yieldably retain the rod 17 in a projected position and the shank portion 16 in engagement with the restricted bore 13 to prevent rotation of the rod 17 and swinging movement of its arm 18. However, by exerting a downward pressure on the rod 17, the spring 19 will be compressed and the head 15 and shank 16 displaced downwardly in the bore 11 to disengage the shank 16 from the bore portion 13 so that the arm 18 may be turned from its operative position over the lever 32, as seen in Figures 1 and 5, to an inoperative position at a right angle to its position of Figures 1 and 5 and parallel to the lever 32, in which position the arm 18 will be held when the shank 16 is projected upwardly by the spring 19 into engagement with the bore portion 13. It will thus be readily apparent that the cross stitch forming attachment need not be removed when not in use as it may be readily positioned in either an operative or inoperative position without disassembling any of the parts thereof. From the foregoing it will be readily apparent that with the arm 18 disposed over the end of the lever 32 which is connected to the needle bar 33, each time that the lever 32 swings upwardly to elevate the needle, not shown carried thereby, said lever will strike the arm 18 for raising said arm and the parts connected thereto to thus cause the tension plate 36 and the presser foot bar 34 to be displaced upwardly thus raising the presser foot, not illustrated in Figures 1 and 5, so that the material being stitched may be turned, thus making it possible to stitch two pieces of material 38

together and which pieces of material 38 have complementary edges thereof in abutting engagement but not in overlapping relationship and are stitched together by a cross stitch as seen at 39 in Figure 8. It will be obvious that each time that the needle bar 33 and presser foot bar 34 move upwardly the pieces of material 38 are turned alternately to the left and to the right.

Figure 6 illustrates the attachment applied to another type of sewing machine known as the "Adler sewing machine" and which likewise includes a lever end 32a which is pivotally connected to the upper end of the needle bar 33a, a presser foot bar 34a which engages under a portion of the free end of a tension plate 36a and which is provided with a tapped recess 37a in its upper end which aligns with a threaded opening 40 of the same diameter in the tension plate 36a. The shank 24 of the connector 20 extends through the opening 40 and into the recess 37a and threaded to connect the tension plate 36a to the upper end of the presser foot bar 34a. The threaded bore end 12 of the barrel 10 engages the threaded body 21 of the connector 20 and mounts the barrel 10 above and perpendicular to the tension plate 36a and said body 21 holds the spring 19 under tension, as previously described in reference to the description of the machine 31, as illustrated in Figures 1 and 5, but enables the attachment arm 18 to be disposed operatively over the lever 32a or in an inoperative position, parallel to said lever. In view of the detailed description of the operation of the attachment, heretofore given, a repetition thereof is considered unnecessary as said attachment operates in the same manner and for the same purpose as heretofore described. However, it will be noted that with the sewing machine 31a, as illustrated in Figure 6, the block 40 24 is omitted.

Figure 7 illustrates the attachment utilized with other of the models of "Singer sewing machines" and wherein the attachment is employed again without the block 24 and additionally without the connector 20. In the machine as illustrated in Figure 7 and designated 31b, the arm 18 in its operative position is again disposed above the end of the lever 32b which is connected to the needle bar 33b. In this form of machine, the presser foot bar 34b is provided with an externally threaded upper end portion 37b which extends through an opening 35b in the free end of the tension plate 36b. A nut normally engages the threaded portion 37b above and below the tension plate 36b to adjustably connect the tension plate thereto. The upper nut, not shown, is removed when the cross stitching attachment is applied but the lower nut 41 remains in place and the threaded bore end 12 is engaged directly with the upper end of the threaded portion 37b so that the connector 20 and block 24 are not necessary. The parts 15, 16, 17, 18 and 19 are employed as in the other assemblies as heretofore described and the spring 19 is held compressed between the upper end of the threaded member 37b and the head 15 and permits adjustment of the arm 18 from its operative position of Figure 7 to a position at a right angle thereto. In Figure 7 a needle 42 is shown connected to the lower end of the needle bar 33b and a presser foot 43 is shown connected to the lower end of the presser foot bar 34b. The needle and presser foot are disposed above the work pieces 38 which are supported on a work plate 44 of the sewing machine. The presser foot and pressure

foot bar are normally urged downwardly by an expansion spring 45 which is mounted on the presser foot bar. The parts 42, 43, 44 and 45 are conventional in the sewing machine 31b and likewise in the sewing machines 31 and 32a, although not illustrated in connection with said other sewing machines. As the operation of the cross stitch sewing attachment as illustrated in Figure 7 is identical with its operation as previously described in detail in connection with the sewing machine 31, a further description thereof is considered unnecessary.

Various modifications and changes are contemplated and may obviously be resorted to, without departing from the spirit or scope of the invention as hereinafter defined by the appended claims.

I claim as my invention:

1. A presser foot lifting attachment for sewing machines comprising a barrel member having a bore extending longitudinally therethrough provided with a restricted upper end, means adapted for detachably connecting the opposite, lower end of the barrel member to the upper end of a sewing machine presser foot bar, a rod extending upwardly from the barrel member and having an angularly disposed free end forming an arm adapted to be normally disposed above the end of the sewing machine lever which is connected to the needle bar and in the path of oscillating movement thereof to be engaged by the lever when the needle bar is elevated for lifting the barrel member and presser foot bar, and means detachably keying the other end of the rod in the barrel member for supporting said angularly disposed free end above the sewing machine lever and at an angle thereto or to one side of and substantially parallel to the sewing machine lever.

2. A presser foot lifting attachment for sewing machines comprising a barrel member having a bore extending longitudinally therethrough provided with a restricted upper end, means adapted for detachably connecting the opposite, lower end of the barrel member to the upper end of a sewing machine presser foot bar, a rod extending upwardly from the barrel member and having an angularly disposed free end forming an arm adapted to be normally disposed above the end of the sewing machine lever which is connected to the needle bar and in the path of oscillating movement thereof to be engaged by the lever when the needle bar is elevated for lifting the barrel member and presser foot bar, a head reciprocally disposed within said bore, said restricted bore end being non-circular in cross section and smaller than said head to limit the upward movement of the head, and said head having a restricted non-circular shank to which the end of the rod which extends upwardly from the barrel member is fixed, said shank being sized and shaped to non-rotatably fit the restricted bore end for detachably keying the rod to the barrel member to retain the arm in an operative position over the lever and crosswise thereof or in an inoperative position to one side of and substantially parallel to the lever.

3. A presser foot lifting attachment for sewing machines comprising a barrel member having a bore extending longitudinally therethrough provided with a restricted upper end, means adapted for detachably connecting the opposite, lower end of the barrel member to the upper end of a sewing machine presser foot bar, a rod extending upwardly from the barrel member and having an

angularly disposed free end forming an arm adapted to be normally disposed above the end of the sewing machine lever which is connected to the needle bar and in the path of oscillating movement thereof to be engaged by the lever when the needle bar is elevated for lifting the barrel member and presser foot bar, a head reciprocally disposed within said bore, said restricted bore end being non-circular in cross section and smaller than said head to limit the upward movement of the head, and said head having a restricted non-circular shank to which the end of the rod which extends upwardly from the barrel member is fixed, said shank being sized and shaped to non-rotatably fit the restricted bore end for detachably keying the rod to the barrel member to retain the arm in an operative position over the lever and crosswise thereof or in an inoperative position to one side of and substantially parallel to the lever, and an expansion spring disposed under tension in said barrel member and bearing against the head to yieldably retain the shank in engagement with the restricted bore position.

4. A presser foot lifting attachment for sewing machines comprising a barrel member having a bore extending longitudinally therethrough provided with a restricted upper end, means adapted for detachably connecting the opposite, lower end of the barrel member to the upper end of a sewing machine presser foot bar, a rod extending upwardly from the barrel member and having an angularly disposed free end forming an arm adapted to be normally disposed above the end of the sewing machine lever which is connected to the needle bar and in the path of oscillating movement thereof to be engaged by the lever when the needle bar is elevated for lifting the barrel member and presser foot bar, said connecting means comprising an internally threaded portion formed in the lower end of said bore adapted to engage the threaded upper end of the presser foot bar to mount the barrel member above and with its lower end in abutting engagement with the sewing machine tension plate.

5. A presser foot lifting attachment for sewing machines comprising a barrel member having a bore extending longitudinally therethrough provided with a restricted upper end, means adapted for detachably connecting the opposite, lower end of the barrel member to the upper end of a sewing machine presser foot bar, a rod extending upwardly from the barrel member and having an angularly disposed free end forming an arm adapted to be normally disposed above the end of the sewing machine lever which is connected to the needle bar and in the path of oscillating movement thereof to be engaged by the lever when the needle bar is elevated for lifting the barrel member and presser foot bar, said bore having an internally threaded lower end, said connecting means comprising a connecting member having an enlarged externally threaded end threadedly engaging in the lower internally threaded end of said bore and a restricted depending threaded shank adapted to extend through a sewing machine tension plate and threadedly engaging in an upwardly opening tapped recess of the presser foot bar.

6. A presser foot lifting attachment for sewing machines comprising a barrel member having a bore extending longitudinally therethrough provided with a restricted upper end, means adapted for detachably connecting the opposite, lower end of the barrel member to the upper end of a sew-

ing machine presser foot bar, a rod extending upwardly from the barrel member and having an angularly disposed free end forming an arm adapted to be normally disposed above the end of the sewing machine lever which is connected to the needle bar and in the path of oscillating movement thereof to be engaged by the lever when the needle bar is elevated for lifting the barrel member and presser foot bar, said connecting means comprising a block having spaced top and bottom walls defining a horizontal recess therebetween opening outwardly of the block and adapted to receive the free end of a tension plate of the sewing machine, the bottom wall of the block having a downwardly opening slot communicating with the recess and adapted to receive the upper end of the presser foot bar which extends into an opening of the tension plate, the top wall of said block having a threaded opening

adapted to align with a tapped upwardly opening recess in the upper end of the presser foot bar, and a connecting member threadedly engaging in the lower end of the bore and having a threaded shank threadedly engaging the threaded opening of the block and the tapped recess of the presser foot bar for connecting said barrel member, block, tension plate and presser foot bar together.
